AIR CONDITIONING APPARATUS

Edward S. Lea, Morrisville, Pa., assignor, by mesne assignments, to George Von Seebeck, New York, N. Y., trustee

Application December 4, 1934, Serial No. 755,916

11 Claims. (Cl. 261—91)

My present invention while capable of embodiment in large size installations is more particularly concerned with the provision of a relatively small compact unit for conditioning air in homes, 5 stores, offices and other relatively restricted enclosures.

An object of the invention is to provide a unit of this character which is a real air conditioner operable in all seasons of the year to filter, wash, 10 deodorize and regulate the temperature and humidity of the air which passes through it while removing all smoke, dust or other foreign particles.

Another object is to provide a compact air conditioning unit of simple, practical, rugged, durable construction consisting of but few parts, 15 silent in operation and convenient to install, easy of access for purposes of cleaning, inspection or repair, requiring but a slight amount of power to operate it and for the most part recirculating the water used to effect thorough washing and proper humidification of the air which passes through it so that the total amount of water used over a long period of time is a negligible 20 factor in the cost of operation.

Another object is to provide a unit in which during summer operation the cooling water is substantially continuously recirculated and in 25 which the water returning from the sprays to the cooling tank automatically establishes a circulation of water in the tank and over the cooling coils which promotes maximum effectiveness of water cooling and the continuous delivery of the coldest water in the tank to the sprays.

Another object of the invention is to provide 30 an apparatus for air washing and humidification, in which the air is first subjected to an extremely heavy forceful spray and subsequently subjected to an extremely fine mist, thorough washing and 35 temperature regulation being effected by the heavy spray, and thorough humidification by the mist.

Another object is to provide an extremely simple apparatus for carrying out the method in 40 which a single motor directly drives one or more rotary water distributors or slingers for creating the heavy washing spray and at the same time drives a fan which serves the four-fold purpose of drawing the air through the heavy sprays, 45 creating the mist, breaking up relatively large drops of water which may enter the mist zone with the previously washed air stream, and supplying the force necessary to expel the air stream through a convolute outlet passage of substantial length but from which the air emerges at 50 100% humidity and at a temperature predetermined primarily by the temperature of the spray water. The convolute outlet passageway removes 55 excess moisture and eliminates remaining solids 60

just as effectively as the zig-zag "scrubbers" now commonly employed, yet opposes far less resistance to the flow of air.

A feature of the invention is the entrapping of some of the water removed in the convolute exit 5 passageway so that the air in traveling the length of this passageway always has evaporative cooling contact with a sheet of water in the bottom of the passageway. In fact all surfaces contacted by the air from the time it enters the unit until it has reached a point close to the outlet of the convolute passageways, are kept constantly wet by sprays or mist.

A compact construction is afforded by the provision of an open bottom casing, the top of which forms part of the convolute outlet passageway. A motor resting on the top of this casing has a pendant shaft driving a fan arranged at the inlet or center of the convolute passageway and below this fan the shaft carries the slingers which lift water from a tank, the latter preferably being 10 removably suspended from the upper casing. A screen encircling the slingers and suspended from the open-bottomed upper casing breaks up the 15 heavy forceful spray from the slingers and the spray substantially fills the space between the 20 bottom of the volute outlet and the surface of the water in the tank, air being drawn in through 25 an inlet opening in the lower portion of the upper casing and all of it being caused to flow counter-currently through the spray thrown outwardly by the slingers and thence through the fan.

Preferably a secondary slinger delivers but a 30 minute quantity of water within the fan and the water from this slinger is drawn into the fan 35 blades and atomized by its impact with them so that an extremely effective humidifying mist zone is created in the region of the fan.

Where cooling coils are used, they are preferably suspended in the tank from the open-bottomed casing and are accessible for ready inspection or cleansing by simply lowering the tank 40 and exposing the coils.

Preferably also the tank has a central well from 45 which water is centrifugally lifted by the slingers, means being provided for maintaining the water in this well substantially quiescent and avoiding a whirlpool effect. The whirling spray delivered by the slingers further serves to set the body of water encircling this well in motion and by arranging the cooling coils so that they completely encircle the well, the water in the tank working downwardly to the lower inlet in the well, will have a continuous rotary motion imparted thereto, whereby it moves substantially in a spiral 50 descending path and is most effectively cooled by the coils.

Another object is to provide an air conditioning unit devoid of spray nozzles, pump valves or 55 60

other minute openings capable of being clogged by sediment in the water, and so to mount the motor that it cannot be wetted and short circuited.

With the above noted and other objects in view, the invention consists of certain novel features of the construction and combinations and arrangement of parts which will be more fully understood from the following description in connection with the accompanying drawings wherein:-

10 Fig. 1 is a vertical sectional view through an air conditioning unit embodying the invention,

Fig. 2 is a sectional plan view therethrough on the line 2—2 of Fig. 1,

15 Fig. 3 is an enlarged vertical sectional detail showing the manner in which the slingers are mounted on the motor shaft and connected to each other,

Fig. 4 is a further enlarged fragmentary transverse sectional detail on the line 4—4 of Fig. 3,

20 Fig. 5 is an enlarged transverse sectional view through the well, on the line 5—5 of Fig. 1,

Fig. 6 is a sectional detail of the motor mount,

Fig. 7 is a sectional detail showing the manner in which the casing is supported and cushioned,

25 Fig. 8 is a perspective view of the apparatus with part of the tank broken away to expose the cooling coil, and

Fig. 9 is a view corresponding to Fig. 1 but illustrating a modification.

30 General construction

Fig. 1 shows the general assemblage consisting of an inverted open-bottomed box-like casing member A, the lower end of which is closed by a 35 water tank B. An air inlet conduit C enters one side of the casing A, a suitable filter D being provided at the mouth of the air inlet. The air outlet E is at the terminal end of a horizontal spiral conduit F disposed in the upper end of the casing 40 A.

An electric motor G resting on the top of the casing A includes a pendant drive shaft H, this shaft mounting a fan J which is disposed at the center of the volute air outlet passageway F. 45 The shaft also carries one or more water distributors K at its lower end, these distributors or slingers being operable to raise water from the tank and sling it radially outwardly through a screen L which encircles the slingers.

50 Another slinger M carried by the shaft H has its outlet end terminating within the open-bottomed fan J, this slinger having a lesser peripheral speed than the slinger or slingers below it and the water which flows from the slinger M is drawn 55 outwardly and into the blades of the fan, where it is broken up into a fine mist. Thus the filtered air entering through the inlet duct C is subjected first to the heavy spray which passes through the screen L and then as it is drawn upwardly into the fan, is subjected to the fine mist in the region of the fan and then forced by the fan through the volute outlet passageway F in which the direction of flow of the air is continuously changed and all of the excess moisture is 60 centrifugally eliminated.

65 The casing

Referring now with more particularity to the casing A, the top of this casing constitutes the 70 top wall of the horizontally disposed volute passageway through which the air is blown by the fan J to the outlet E. The bottom wall of the volute passageway F provides a downwardly facing frusto-conical mouth portion 10 for directing the up-flowing air which is passed through the

heavy sprays, into the open-bottomed, closed-topped fan J, the latter being preferably of the sirocco type. The screen L which breaks up the heavy spray from the lower slingers K is preferably supported from the casing A as by supporting arms or brackets 11 secured to the bottom forming plate of the spiral passageway F.

For reasons to be more fully hereinafter described it is desirable to maintain the bottom of the passageway F covered with water to a level 10 predetermined by an overflow pipe 12 the lower end of which terminates below the water level in the tank B.

The inlet conduit C preferably extends the full width of one side of the casing, the latter being 15 herein illustrated as rectangular and the inlet end of the conduit C extends upwardly above the casing top and is rectangular in cross section as indicated at 13 providing means for removably mounting a filter unit such as D. This unit may 20 be slid through an opening (not shown) in one side of the duct portion 13 and slid into place between guide rails 14, to the end that the filter units may be readily withdrawn and renewed 25 as desired.

The tank

Preferably the tank B is of the same cross sectional shape as the casing A but of slightly greater cross sectional area, whereby the lower end of the 30 box-like casing A may be immersed in the water in the tank. The inlet pipe 15 through which water is delivered to the tank is preferably mounted in the casing A.

If it is desired to cool the water in the tank 35 B, cooling coils 16 are preferably suspended directly from the casing A as by suspension rods 17 and the inlet and outlet headers 18 and 19 for the refrigerant coils 16 communicate with inlet and outlet pipes 19' and 20' which also extend upwardly through the top of the casing A and terminate above it.

The casing and tank are so assembled that the tank may be lowered to expose the cooling coils 16 and render them readily accessible for 45 purposes of cleaning. Such ready removal of the tank will also permit convenient removal from the tank of sediment which may have settled therein. As suggested in my Reissue Patent No. 20,341 the casing A may be suspended from the ceiling, typically a basement ceiling and the tank removably supported by the casing itself.

Fig. 8 shows another convenient method of removably supporting the casing and the tank in 50 cooperative relationship so that the tank may be lowered when required. This includes a housing and support unit for the tank and casing, the unit being of square horizontal cross section, open at its top and at its front. The side walls 22 of this unit, as well as the rear wall thereof, (not 55 shown) are secured at their edges to rectangular frame structures 23, these frame structures including angle irons or other suitable ledge forming means 24 at their tops, adapted to support the casing. The casing for this purpose is provided with laterally extending brackets 25 (Fig. 7) having sockets 26 in their under faces receiving rubber feet or blocks 27 which rest upon the ledge forming members 24. Pendant latch members 28 carried by the outer wall of the casing engage 60 hooks 29 on the outer walls of the tank so that the tank is suspended from the casing.

Rising from the bottom of the tank B is a well-forming member 30 of sufficient height to 70 extend above the water level in the tank. Water 75

flows into the bottom of this well, through a pivoted valve plate 31, the valve being opened by a push rod 32 extending through the casing A. A spring 33 normally tends to elevate this rod and the rod is depressed to open the pivoted valve by a control lever 34 actuated from any suitable means as for instance a thermostatic bellows (not shown). The lower ends of the nested slingers K are immersed in the water of the well 30 and to prevent a whirlpool effect, baffles 35 may extend inwardly from the walls of the well.

Motor, fan and slingers

The casing of the motor G is provided with a relatively wide annular flange 36 and the motor rests by gravity upon the casing A, being suitably cushioned to prevent vibration or slippage of the motor. For this purpose an annular rubber gasket 37 (Fig. 6) fits within a circular collar 38 rising from the top of the casing. The gasket includes an inwardly extending flange portion 37a having a sharply corrugated upper surface indicated at 37b and the flange 36 of the motor casing G rests upon the corrugated gasket surface compressing the corrugations to the desired extent so that snug seating occurs, this annular flange 36 fitting snugly within the thicker outer portion 37 of the gasket.

The purpose of corrugations is merely to render that portion of the rubber gasket upon which the motor seats more readily compressible and distortable to insure tight seating of the flange 36 thereon. The fan H is secured upon a hub 40, the hub in turn being affixed to the pendant motor shaft H. An opening 41 in the top of the casing A of slightly greater internal diameter than the maximum external diameter of the fan permits the fan to be attached to the motor shaft and then to be lowered in place through the casing top as the motor G is lowered onto its seat.

Various expedients may be resorted to for securing the distributors or slingers to the motor shaft and in Figs. 3 and 4 I have illustrated one satisfactory method of mounting a plurality of nested slingers concentrically with respect to the shaft. Each of the lower slingers K includes a generally conical shell 45, the mouth of which flares outwardly in a substantially horizontal plane as indicated at 46. Radially disposed ribs 47 mounted on the edges of the horizontal portions of the shells serve to add impetus to the water which is flung circumferentially by the slingers when the latter are rotated. The lower reduced end of each shell 45 carries an internal hub 45a in the nature of a spider, the hub of each slinger fitting over the shell portion of the next adjacent slinger and all of the hubs being connected together and secured to the shaft H by elongated set screws 86 passed through registering openings in the solid portions of the spider-like hubs and into engagement with the shaft. Only the innermost hub is threaded for reception of these screws, the outer hubs being provided with elongated openings 87 through which the screws freely pass.

In Fig. 3 I have illustrated three of the generally conical slingers K nested one with the other, with the edges of all of the slingers terminating in the same vertical plane and with the horizontal portions of the slingers closely overlapping each other. Preferably a baffle plate 50 is arranged immediately above the innermost and uppermost of these slingers K to prevent the water from being thrown in an upward direction. No baffles are required for the lower slingers since

the slingers above them serve effectively as baffles.

The innermost slinger M is of generally tubular formation throughout the greater portion of its length, tapering inwardly near its bottom and tapering only slightly outwardly at its top as indicated at 51. The baffle 50 may be provided with a collar 52 welded to the tubular slinger M. Preferably the conical shell of each of the slingers K includes a generally horizontally disposed offset portion 53, these offsets having apertures therein through which tie rods 54 may pass. These rods likewise extend through the baffle 50 and nuts 55 screwed onto the lower ends of the rods tend to tie all of the slinger members together to supplement the screws 86 and draw the slingers into compactly nested relationship.

Extremely accurate machining of the hubs or extremely accurate spinning of the conical shells K are not necessary since the openings 87 compensate for slight machining or spinning inaccuracies and tightening of the tie rods 54 pulls the shells into snugly nested relationship regardless of whether the openings 87 are in direct alignment or not.

As the nested hubs of the conical shells, slingers or distributors K rotate in the water in the well 30, the water is drawn upwardly along the inner wall of each slinger and is flung centrifugally from the mouths of these slingers with considerable violence, driving through the screen L which breaks up this heavy forceful spray to some extent and causes the spray to be projected fanwise into the space between the screen and the side walls of the casing. The space between the water level and the bottom of the spiral chamber is substantially filled with the heavy spray which has passed through the screen, it being borne in mind that the water which passes through this screen is simultaneously acted upon by three different forces. First the centrifugal force which has projected it through the screen; secondly, the force of gravity; and thirdly, by the up-draft of the fan. The result of these forces is to substantially fill the entire space between the bottom of spiral chamber F and the water level and outwardly beyond the fan with a very heavy spray which washes and cools the air entering the apparatus through the duct C.

The water travels rather slowly up the distributor M however, and since this distributor is traveling at much lower peripheral speed than the slingers K, a relatively thin sheet of water is projected radially from the mouth of the slinger. This less forceful spray is drawn practically in a horizontal direction by the fan suction into contact with the fan blades and since the fan is traveling at a substantial peripheral speed, the radial spray from the mouth of the slinger M is broken up into a fine mist by impact with the fan blades. Part of this mist is driven back into the fan and part of it is blown beyond the fan into the spiral passageway and part of it tends to settle downwardly and commingle with the thoroughly washed air stream which has passed through the heavy spray and is moving upwardly into the fan, carrying with it some drops of water of relatively large size. These drops upon striking the fan are finely subdivided and converted into mist.

The whirling spray afforded by the lower slingers K tends to impart a whirling or rotary motion to the body of water in the tank B. This is particularly advantageous for purposes of cooling water, especially in conjunction with the ar-

5 arrangement of a water entrance at the lower end only of the well. Ordinarily the water in the well will be at such a temperature that convection circulation thereof over the cooling coils will be negligible but by drawing water always from the bottom of the tank into the well and by rotating the body of water in the tank, the water at the top of the tank will move gradually toward the bottom of the tank and during this movement 10 will be progressively swirling over the series of cooling coils so that heat interchange between the water and the coils is promoted. This swirling motion of the water also aids in keeping the coils clean.

15 Windows 60 arranged in the casing A and registering with openings in the outer shell 22 permit the operation of the device to be continuously inspected at all times and the speed of the motor for instance accordingly adjusted. 20 Preferably the pivoted valve 31 is merely a rough casting which does not seat snugly so that a certain amount of water is always leaking into the well 30 and some slight amount of water is being distributed by the slingers even when the valve is 25 in its closed position.

30 It will be observed by reference to Fig. 2 that the convolute chamber through which air is advanced by the fan toward the outlet is of progressively increasing cross sectional shape. In 35 other words it is a true spiral so that the air traveling through it is subjected to a continuous change of direction to expedite the removal therefrom of all excess moisture and insure delivery at the outlet of the machine of 100% 40 humidified air carrying no excess entrained moisture.

45 By using an overflow inlet such as 12, the bottom of the spiral or convolute outlet passageway is always covered with water and additional evaporative cooling is obtained. In fact from the time the air approaches the lower end of the conduit C until the time it is half way through the convolute outlet passageway, every surface which it contacts is a wet surface so that the maximum 50 evaporative cooling in addition to direct cooling by the sprays is obtained. The air drawn into the duct C tends to advance around all sides of the screen K and to be drawn in a vortex into the fan after having countercurrent through the spray thrown outwardly by the lower slingers K. No air is permitted to by-pass these sprays and since the entire region of the fan is practically 55 filled with a fine mist, thorough humidification of the air is assured. The excess moisture removed by centrifugal force from the air which has advanced through the convolute passageway, drains down the walls of this chamber and the excess flows through the pipe 12, the overflow being silent due to the immersion of the lower end of 60 the pipe in the water tank.

65 The compactness of the unit will be apparent from the foregoing description. Practically every available cubic foot of space is utilized. The convolute passageway while of substantial length is confined within a relatively small volumetric space. The space between the bottom of this convolute discharge passageway and the water level in the tank is but slight and it is entirely 70 filled with heavy spray. The center of the passageway F is occupied by the fan. The slingers K are disposed at but a slight distance below the fan and the vertical space occupied by the entire unit is reduced to a minimum. When no refrigerant coils are in use, the tank may of course 75 be very much shallower to further conserve verti-

cal space and the height of the entire unit need not be more than a couple of feet. A great economy of materials as well as space is thus afforded. The water in the tank is preferably recirculated over and over again, this being particularly advantageous in the winter time when no cooling is desired since the water will quickly assume the temperature of the air and the device will simply act as a humidifier and not as a cooler. No special control for maintaining a constant water level or a slow inflow and outflow from the tank has been shown but means may be obviously utilized if desired.

80 I have not shown any ducts connected either to the inlet or outlet of the machine but for the purpose of ventilating a private home or other relatively small enclosure the arrangement of ducts may be extremely simple, consisting merely of one outlet duct and one inlet duct arranged respectively in the lower floor and one in the 85 upper floor of the house, the ducts being reversible for the delivery of cold air at the top of the house in summer or warm moist air in the lower part of the house in winter, it merely being necessary to change the duct connections from the 90 inlet to the outlet connections of the machine to reverse them for winter and summer use.

95 Obviously the cooling coil may be supplied from any source of refrigerant but an ordinary household ice box unit is adequate for effecting the refrigeration desired. In localities where relatively cool reservoir water is available and where water is cheap, the refrigerating unit may be dispensed with even in the summer time. Insofar as the control of the mechanism is concerned, any of various standard controls may be used. For the simplest form of operation I simply use a humidistat or thermostat to cut the motor in and out. With the type of installation shown, thermostatically or humidistically 100 controlled means are operative to close or open the valve which admits water to the well and the motor runs continuously so that circulation of air is always maintained. In this connection it is worthy of note that the inlet end of slinger M terminates below the lower ends of slingers K. By allowing a slow leak through valve a certain amount of water will always flow from slinger M to effect creation of a mist in the region of the fan and to humidify all air passing through 105 the spray even when there is no water available for the spray creating slingers K. Where it is desirable to maintain a continuous washing action of the air without substantial humidification thereof, it will of course be apparent that the inlet end of the slinger M may terminate above the lower ends of the slingers K. The principle involved is permitting one slinger to rob the other of water when the valve is closed. More complex controls might of course be utilized if desired, it being perfectly apparent that by the simple procedure of regulating the 110 temperature of the refrigerant or other temperature changing medium utilized, both the temperature and humidity of the air within an enclosure could be accurately controlled within narrow limitations. Heaters at the inlet or outlet of the machine might be employed, if desired, in the winter time but their use is conventional and they have not been illustrated. 115 The present machine is primarily designed to insure a uniform humidity for any given air temperature, maintaining the humidity comfortably high in the winter time and comfortably low in the summer time. In fact where a rela- 120

tively small capacity refrigerating machine is utilized, most of the energy developed in the refrigerating machine will be used in extremely hot weather for absorbing latent heat from the hot air which enters the machine and even though the unit exerts no appreciable cooling effect on extremely hot days, it will have a very marked effect on humidity. In other words, the unit is primarily designed to provide a compact, inexpensive apparatus requiring but slight power to operate and serving the very practical purpose of keeping the air within a house or other enclosure comfortable and clean and in motion. The maintenance of a sufficiently high humidity in winter and of sufficiently low humidity in summer are factors being of considerably more importance than variation of temperature within a few degrees one way or the other.

The use of a plurality of nested slingers for the production of the heavy spray is entirely optional, depending upon the volume of air to be handled and the particular screen arrangement herein utilized is also subject to many changes within the scope of the invention.

In Fig. 9 I have illustrated a slight modification in which the tank B has been replaced by a much shallower tank B'. This type of tank may be used in the winter time or wherever no refrigeration of the water is required. The well and its inlet valve are omitted and a pair of L-shaped brackets 90 are secured to the tank bottom, the upstanding legs of these brackets being arranged close to the slingers and serving to sufficiently baffle the flow of water in the region of the slingers to prevent a whirlpool or cavitation effect. I have likewise shown the screen L as supplemented by a second screen L', the latter screen being pendant from the bottom plate of the convolute casing F and being disposed concentrically with but at a substantial radial distance from the screen L. The screen L' preferably has its lower end immersed in the water in the tank so that the water which drains down it will flow silently into the tank. By virtue of this arrangement the water, after passing through the screen L will strike the screen L'; some of it will splash back toward the center of the tank and much of it will pass through the screen L' and be projected in a further subdivided spray into the path of the inflowing air. The particular mesh of the screens utilized and their distance from the peripheral edges of the slingers are all factors which determine the nature of the washing and cooling spray. I may omit the central screen altogether, in which case much less noise is created by the water striking the outer screen, the latter in this case being of relatively fine mesh, particularly at the point where the heaviest part of the spray strikes.

In Fig. 9 it will also be observed that I have used a single slinger K in conjunction with the slinger M and the arrangement of tank, screens and slingers illustrated in Fig. 9 is of course considerably less expensive than that previously described. Small units of the character shown in Fig. 9 are particularly effective where cold water is available in the city mains, or for the purpose of maintaining the proper humidity of air in winter time. Where these units are used for cooling, of course a substantially continuous flow of water should be maintained in the tanks but where they are used for merely humidifying purposes, the water is constantly recirculated and will ultimately reach a temperature ap-

proximating that of the air passing through the machine.

It will thus be seen that there is herein described a method and apparatus in which the several features of this invention are embodied, and which method and apparatus in their action attain the various objects of the invention and are well suited to meet the requirements of practical use.

As many changes could be made in the above construction, and many apparently widely different embodiments of this invention could be made without departing from the scope thereof, it is intended that all matter contained in the above description or shown in the accompanying drawings shall be interpreted as illustrative and not in a limiting sense.

Having thus described my invention, what I claim as new and desire to secure by Letters Patent is:—

1. An air conditioning apparatus including an open-bottomed casing, a water receiving tank constituting a displaceable bottom for said casing, said casing having an air inlet and an air outlet therein, fan means within the casing for inducing flow of air from the inlet to the outlet, air spraying means in the casing drawing water from the tank, coils in the tank for regulating the temperature of the water, means suspending said coils from the casing and means permitting lowering said tank with respect to the casing to thereby expose the coils.

2. An air conditioning apparatus including an open-bottomed casing, a water receiving tank constituting a displaceable bottom for said casing, said casing having an air inlet and an air outlet therein, fan means within the casing for inducing flow of air from the inlet to the outlet, air spraying means in the casing drawing water from the tank, coils in the tank for regulating the temperature of the water, means suspending said coils from the casing, means to permit downward displacement of said tank with respect to the casing to expose the coils, inlet and outlet conduits for temperature changing fluid connected to the coils and extending through the casing.

3. An air conditioning unit of the class described including a housing, the lower end of which constitutes a water tank, a motor disposed above the housing and a motor shaft extending downwardly into the housing, a fan carried by the motor shaft near the upper end of the housing and a volute air outlet passage encircling fan and into which air is discharged by the fan, a centrifugal rotary water elevator and slinger carried by the lower end of the shaft having its lower end immersed in the water of the tank and discharging below the level of the volute, and means for directing a water spray into the fan to be broken up thereby and create a fine humidifying mist at the inner portion of the volute, an air inlet in the housing arranged so that the air therefrom is drawn through the spray from the slinger by the fan.

4. An air conditioning unit of the class described including a housing, the lower end of which constitutes a water tank, a motor disposed above the housing and a motor shaft extending downwardly into the housing, a fan carried by the motor shaft near the upper end of the housing and a volute air outlet passage into which air is discharged by the fan, a centrifugal rotary water elevator and slinger carried by the lower end of the shaft having its lower end immersed in the water of the tank, an air inlet in the hous-

- ing arranged so that the air therefrom is drawn through the spray from the slinger by the fan, a second slinger of greater height and less maximum diameter than the first slinger for delivering a spray of water within the fan to be broken up into a mist by contact with the fan blades, a well in the tank, a valve controlling flow of water into the lower end of the well and adapted to permit even in closed position a slight leakage of water into the well, said slingers drawing water from the well, one slinger extending below the other slinger whereby upon slow leakage of water into the well substantially only said longer slinger will draw water from the well.
5. In a unit of the class described, a housing, a water tank constituting the bottom of the housing and an open-bottomed casing constituting the top of the housing, a horizontally disposed, doubly convolute air outlet passageway in the top of the housing, a motor supported upon the top of the housing, a motor shaft extending downwardly and inwardly into the housing, a fan fixed on the motor shaft at the center of the volute passageway, an air inlet at one side of the housing above the water level and below the volute passageway, a centrifugal water slinger carried by the shaft and discharging in the space between the water level and the bottom plate of the volute passageway and a baffle means coacting with the upper surface of said slinger to direct the spray from said slinger substantially radially outwardly and a second slinger also drawing water from the well and directing it radially outwardly into the fan.
6. In a unit of the class described, a housing, a water tank constituting the bottom of the housing and an open-bottomed casing constituting the top of the housing, a horizontally disposed, doubly convolute air outlet passageway in the top of the housing, a motor supported upon the top of the housing, a motor shaft extending downwardly and inwardly into the housing, a fan fixed on the motor shaft at the center of the volute passageway, an air inlet at one side of the housing above the water level and below the volute passageway, a centrifugal water slinger carried by the shaft and discharging in the space between the water level and the bottom plate of the volute passageway and a screen encircling the periphery of the slinger for breaking up the spray.
7. In a unit of the class described, a housing, a water tank constituting the bottom of the housing and an open-bottomed casing constituting the top of the housing, a horizontally disposed, doubly convolute air outlet passageway in the top of the housing, a motor supported upon the top of the housing, a motor shaft extending downwardly and inwardly into the housing, a fan fixed on the motor shaft at the center of the volute passageway, an air inlet at one side of the housing above the water level and below the volute passageway, a centrifugal water slinger carried by the shaft and discharging in the space between the water level and the bottom plate of the volute passageway and a screen encircling the periphery of the slinger for breaking up the spray, means for supporting said screen from the lower wall of the volute passageway.
8. In a unit of the class described, a housing, a water tank constituting the bottom of the housing and an open-bottomed casing constituting the top of the housing, a horizontally disposed, doubly convolute air outlet passageway
- in the top of the housing, a motor supported upon the top of the housing, a motor shaft extending downwardly and inwardly into the housing, a fan fixed on the motor shaft at the center of the volute passageway, an air inlet at one side of the housing above the water level and below the volute passageway, a centrifugal water slinger carried by the shaft and discharging in the space between the water level and the bottom plate of the volute passageway, a second slinger fixed to the motor shaft, traveling at less peripheral speed than the first slinger and having its discharge end disposed within the fan.
9. In a unit of the class described, a housing, a water tank constituting the bottom of the housing and an open-bottomed casing constituting the top of the housing, a horizontally disposed, doubly convolute air outlet passageway in the top of the housing, a motor supported upon the top of the housing, a motor shaft extending downwardly and inwardly into the housing, a fan fixed on the motor shaft at the center of the volute passageway, an air inlet at one side of the housing above the water level and below the volute passageway, a centrifugal water slinger carried by the shaft and discharging in the space between the water level and the bottom plate of the volute passageway and a baffle means coacting with the upper surface of said slinger to direct the spray from said slinger substantially radially outwardly, a second slinger fixed to the motor shaft, traveling at less peripheral speed than the first slinger and having its discharge end disposed within the fan, said baffle means being carried by said second mentioned slinger.
10. In a unit of the class described, a housing, a water tank constituting the bottom of the housing and an open-bottomed casing constituting the top of the housing, a horizontally disposed, doubly convolute air outlet passageway in the top of the housing, a motor supported upon the top of the housing, a motor shaft extending downwardly and inwardly into the housing, a fan fixed on the motor shaft at the center of the volute passageway, an air inlet at one side of the housing above the water level and below the volute passageway, a centrifugal water slinger carried by the shaft and discharging in the space between the water level and the bottom plate of the volute passageway, a second water slinger carried by the shaft and discharging into the fan.
11. An air conditioning unit of the class described including a casing, a tank at the bottom thereof, a motor disposed above the housing and a motor shaft extending downwardly into the housing, a fan carried by the motor shaft near the upper end of the housing and a volute air outlet passage into which air is discharged by the fan, a rotary water distributor carried by the lower end of the shaft having its lower end immersed in the water of the tank, an air inlet in the housing arranged so that the air therefrom is drawn through the spray from the distributor by the fan, a second distributor carried by the shaft for delivering a spray of water within the fan to be broken up into a mist by contact with the fan blades, said second mentioned distributor delivering a relatively light low velocity spray and said first mentioned distributor delivering a relatively heavy high velocity spray.
